SNAP ACTING THERMAL DEVICE

Edwin O. Blodgett, Rochester, N. Y., assignor to
General Railway Signal Company, Rochester,
N. Y.

Application May 13, 1931, Serial No. 536,991

11 Claims. (Cl. 200—122)

This invention relates to time-element devices and more particularly to thermal-electric time-element devices having definite snap action.

Thermal-electric time-element devices of the usual type employ a heating element to distort a thermostatic element and thereby function to operate contact means or the like. Such devices necessarily actuate such contact means very slowly which involves well known disadvantages in making or breaking circuits carrying a substantial amount of current or having a very great impressed voltage. These thermostatic elements also have a definite shape or position to which they automatically return after de-energization of the heating element.

In view of the above, it is proposed, in accordance with this invention, to provide a thermal-electric device which is operable to either of two retained positions and which has an inherent snap action after a definite period of energization.

Other objects, purposes and characteristic features of the present invention will appear as the description thereof progresses, during which references will be made to the accompanying drawing which shows the invention in a manner to make it easily understood, rather than with the view of showing the particular construction preferably employed in practice, and in which:—

Fig. 1 is a plan view of a device constructed according to this invention;

Fig. 2 is a sectional view on line 2—2 of Fig. 1 viewed in the direction indicated by the arrows; and

Fig. 3 is an elevational view of a modified device also embodying the present invention.

The thermal-electric device illustrated in the embodiment of the invention shown in Figs. 1 and 2, comprises two bi-metallic strips 1 and 2 each having one end secured to a movable member 3 and the other end to a fixed member 4 by suitable means such as rivets 5, as shown. The member 3 is slidably attached to the member 4 by suitable means such as the rivets 6 and 7 which pass through slots in the member 3 and are fixed in the member 4. The heads of the rivets 6 and 7 are arranged to retain the member 3 yet permit a slight linear motion of the member 3 on the member 4.

The centers of the bi-metallic strips 1 and 2 are rigidly interconnected by a rod 8 preferably of insulating material and may be held by metal inserts 9 which pass through holes in the strips 1 and 2 and are threaded into the rod 8. Similar insulating rods 10 and 11 may also screw on the other ends of the inserts 9 to securely clamp the

strips 1 and 2 and may also serve to operate contact means.

The member 3 is biased inwardly on the member 4 by a spring 12 which is held between the member 3 and an extension of the member 4 by an adjustable screw 13 passing through a hole in the extension and being tapped into the member 3. This biasing spring 12 is sufficiently strong to cause the strips 1 and 2 to buckle to a curved position either side of center, and the extent of this buckling is adjusted by the screw 13 which directly limits the inward motion of the member 3 on the member 4.

The bi-metallic strips 1 and 2 are constructed in the conventional way by employing two metals whose differential expansion distorts the member when subjected to temperature changes. These strips 1 and 2 are oppositely arranged on the members 3 and 4, that is, so that like temperature changes tend to produce opposite directions of distortions therein. These strips may, of course, be thus arranged in either of two ways but in this disclosure it will be considered that each strip has the metal of the greater coefficient of expansion on the inside of the device in Fig. 1. Electrical heating elements 14 and 15 are wound each side of the center rod 8 over suitable material to electrically insulate the windings of the elements from the bi-metallic strips. Each end of these elements may be connected to the device as shown and energy applied to the center of each element from individual circuits which use the strips or the metal frame of the device as a common connection thereto.

Considering that the strips 1 and 2 have been buckled or biased to the position shown in Fig. 1, it is evident that the energization of the heating element 15 tends to warp the bi-metallic strip 2 to a straight position because the inside metal of this strip has the greater coefficient of expansion and obviously tends to distort the strip in a direction opposite to the buckle produced by the biasing spring 12. This straightening of the strip 2 also straightens the strip 1 through the connecting rod 8, and the member 3 is obviously forced along the member 4 against the biasing spring 12. When these strips 1 and 2 are thus forced slightly beyond center they are quickly buckled to an oppositely curved position by the biasing spring 12.

The reverse operation to the one just described is similarly accomplished by energizing the heating element 14 which straightens the strips by warping the reversed strip 1 and obviously the strips are likewise snapped to the position shown in Fig. 1 when they reach a slight beyond-center

position. It is now obvious that the bi-metallic strips are retained in either of such extreme operated positions by the biasing spring 12 until the energization of the opposite heating element.

5 This thermal electric device may be employed to operate various means but it has been illustrated as operating a spring contact arrangement and it is desired to be understood that this is shown only by way of illustrating the utility of 10 the device. A support 16 may be secured to the member 4 by suitable means such as by rivets 17 to thereby provide a contact mounting means.

The contact arrangement shown consists of 15 movable resilient contact springs 18 operable by the rods 10 and 11 to engage with either front or back fixed resilient contact springs 19 at low resistance contact points. These fixed contact springs have rigid stops 20 assembled together with the contact springs 18 and 19 between insulating spacers 21 by through bolts 22 which have insulated body bushings and clamp the assembly to upstanding ends of the support 16. Short insulated terminal strips 23 and a strip 25 connected to the metal of the device may also be 20 secured to the support 16 in a similar manner for terminating the leads from the heating elements 14 and 15 thereby facilitating in making external connections.

It will be noted in the device that the amount 25 of buckle in the bi-metallic strips 1 and 2 is readily adjustable by the screw 13 which is threaded into the member 3. The body of this screw 13 freely passes through an enlarged hole in the extension of the member 4 when the operation of 30 the device actuates the member 3 but the enlarged head of the screw 13 engages the extension of the member 4 to stop the biased inward motion of the member 3. It is obvious that the operation of such a device is unaffected by changes in temperature so long as both elements are of substantially the same temperature because the opposing arrangement of the bi-metallic strips produces only stress between the strips and no change in 35 position thereof, relative to the frame of the device.

The modified form of the present invention illustrated in Fig. 3 has a single operating strip only and consequently is electrically operable to only one position. A manual operable means 24, 40 which may be termed a manual reset, is secured to the strip 21 and arranged to pass through an enlarged slot in the member 31 and a suitable hole in the member 41. A contact arrangement similar to that of Fig. 1 is illustrated as being operated by the modified device but it is understood 45 that this device is also applicable to operate various other functions as well.

The electrical operation of the device in Fig. 3 is accomplished by passing sufficient electrical 50 current through the heating element 151 which distorts the bi-metallic strip 21 which is arranged with the metal of larger coefficient of expansion on the inside or the same side as the manual reset 24. This causes the same operation of the 55 strip 21 as was previously described and the strip is then retained in a position opposite to that shown until manually reset by pressing the reset means 24.

It is also contemplated to construct a device 60 similar to that shown in Fig. 3 with the manual reset 24 omitted and having a bi-metallic strip in place of the strip 21 which is constructed with a normal bend in a shape curved in the opposite direction to that which it assumes when heated 65 above the normal temperature. In other words,

this device would have an operating strip arranged as in Fig. 3 but with a permanent set in the curved shape shown when unbiased by the spring 12, and this permanent set would be so adjusted to exert a greater force tending to return the strip, when at the normal temperature, to its set shape than is exerted by the spring 12 to retain the strip in its beyond center operated position. It is obvious that the energization of the heating element on such a strip would cause 10 it to buckle to a position curved opposite to the permanent set therein and the strip would again snap back to its original or set shape when its temperature had returned to normal.

It will now be seen that a thermal-electric 15 device has been provided which may be employed to actuate contacts or the like to a definite position after a predetermined length of time and may be arranged to either automatically return to its original condition a predetermined time 20 after each operation or to retain such a position until returned either manually or by a reversed thermal-electric means.

The above description of the forms of the present invention is given solely by the way of example, and is not intended, in any manner whatsoever, in a limiting sense. It is also to be understood that various modifications, adaptations and alterations may be applied to meet the requirements of practice, without in any manner 30 departing from the spirit or scope of the present invention, except as limited by the appended claims.

Having thus described my invention, what I 35 claim is:—

1. In a thermal-electric device, two opposed thermo-responsive strips, a rigid support at each end of said strips, compression biasing means on said supports arranged to produce a longitudinal buckle in said strips, individual electrical heating elements associated with each strip and means rigidly interconnecting intermediate portions of said strips.

2. In a thermal-electric device, two substantially parallel thermo-responsive elements oppositely arranged with an intermediate rigid connection, end supports for said thermo-responsive elements having inward biasing means arranged to buckle said elements to a curved position and individual heating units for said thermo-sensitive 50 elements.

3. In a thermal-electric device, two longitudinally resilient supporting members, two spring bi-metallic strips arranged to longitudinally spread said supporting members when straight, 55 said bi-metallic strips being arranged in parallel and opposite relation and having an intermediate interconnection.

4. In combination, two substantially fixed supports, two oppositely arranged bi-metallic strips held between said two fixed supports and having a length greater than the distance between said two supports, means heating one or the other of said bi-metallic strips whereby said bi-metallic strips are operated to either of two positions and means operated in accordance with the two positions of said bi-metallic strips.

5. In a thermal electric device, two spaced parallel bi-metallic strips arranged in opposite relation, means interconnecting intermediate portions of the strips, a member interconnecting the one end of the strips, a second member connecting the other ends of the strips and arranged to move longitudinally with respect to each other, a spring biasing said second member toward said 75

- first member whereby said bi-metallic strips are biased to either of two curved positions, an adjustable means limiting the inwardly biased position of said second member, an electric heating element associated with one of said strips for operating both strips to one of said curved positions, a similar element on the other of said strips for operating both strips to the other of said curved positions and contact means operated in accordance with the curved positions of said strips. 5
6. In a thermal-electric relay, a bi-metallic strip, a member carrying one end of said strip, a second member carrying the other end of said strip and guided for motion longitudinally on said first member, a spring inwardly biasing said second member on said first member whereby said bi-metallic strip is buckled to a curved position to either side of center, an adjustable stop 10 for said inwardly biased movement of said second member, an electric heating element arranged to warp said bi-metallic strip to a curved position one side of center, a manually operable means for positioning said strip the other side of center and contact means operated in accordance 15 with the position of said strip.
7. In a thermal-electric device, two thermo-responsive operating means, biasing means arranged to buckle each operating means to either 20 of two extreme positions when either is actuated beyond a central position and heating means for actuating both operating means to either of said beyond center positions.
8. In a thermal-electric device, two substantially parallel thermo-responsive elements oppositely arranged with an intermediate rigid con- 25
- nection, and supports for said thermo-responsive elements arranged to buckle said elements to a curved position and individual heating units for said thermo-sensitive elements.
9. In combination, two supports, two oppositely arranged bi-metallic strips held between said two supports and having a length greater than the distance between said two supports, means heating one or the other of said bi-metallic strips whereby said bi-metallic strips are operated to 10 either of two positions and means operated in accordance with the two positions of said bi-metallic strips. 5
10. In a thermal-electric device, a thermo-responsive strip, a first support at one end of the strip, a second support at the other end of the strip, means biasing the first support relatively to the second support along the line of said strip in a manner to longitudinally curve the strip either side of its normal straight position, an 20 electric heating element arranged to operate said strip to one longitudinally curved position and a member extending from an intermediate portion of said strip to permit manual operation of the strip to the other longitudinally curved position. 25
11. In combination, a thermo-responsive strip, biasing means acting in a plane parallel to the strip to longitudinally flex the strip and operable to normally hold the strip in either of two curved positions, an electric heating means for operating the strip to one curved position, manual means fixed to an intermediate portion of the strip for operating the strip to the other curved position and contact means operated in accordance with the curved position of the strip. 30 35
